MACHINE FOR BRUSHING, JACKING, AND SIZING HATS.

1,114,547.

Specification of Letters Patent.

Patented Oct. 20, 1914.

Application filed March 11, 1914. Serial No. 823,877.

To all whom it may concern:

Be it known that we, JOHN H. STARR and JAMES F. DORAN, citizens of the United States, residing at Danbury, county of Fairfield, State of Connecticut, have invented an Improvement in Machines for Brushing, Jacking, and Sizing Hats, of which the following is a specification.

This invention relates to machines employed in the manufacture of felt hats, and more particularly in the operations known as jacking, brushing, and sizing, and has for its general object to provide an easily operated, thoroughly effective, and generally improved machine for performing any or all of these operations.

With this and other objects in view the invention consists in certain constructions and in certain parts, improvements, and combinations which will be hereinafter described and then particularly pointed out in the claims hereunto appended.

In the accompanying drawings forming a part of this specification: Figure 1 is a plan view of the machine with the aprons or guides for the work omitted. Fig. 2 is a side elevation with the roll shafts and tank in section. Fig. 3 is a substantially central longitudinal vertical section. Fig. 4 is an end elevation with the tank in section. Fig. 5 is a detail end elevation of the roll frames and associated parts. Fig. 6 is a detail perspective view illustrating the construction of one of the rolls. Fig. 7 is a detail perspective view of one of the caps for holding the parts of a roll in assembled position on the shaft. Fig. 8 is an enlarged elevation of a modified construction of the mechanism for oscillating the roll frames. Fig. 9 is an elevation of the parts shown in Fig. 8, as viewed from the left in the latter figure. Fig. 10 is a perspective view of one of the rolls employed in the sizing operation. Fig. 11 is a similar view of a modified form of sizing roller. Fig. 12 is a partial longitudinal vertical section of the machine illustrating an arrangement of rollers suitable for performing the sizing operation.

As will be understood by those familiar with the art, the operation known as "jacking" is performed upon a hat body to cause the fibers on the outside thereof to be partially disengaged from the felted body so as to stand out or protrude in the form of a

raised nap. It is desirable that this operation be performed by means which will not break or otherwise injure the fibers, which will not entirely remove said fibers to any considerable extent, which will tend to withdraw the tip rather than the butt end of each fiber, and which will not unnecessarily tend to disintegrate the body as a whole.

The operation known as "brushing" follows that of jacking and consists in brushing the fibers or nap raised by the jacking operation for the purpose of cleaning, polishing and straightening out the fibers and also of thickening the napped surface by bringing out fibers which may have been partially loosened by the jacking operation. This brushing operation is usually performed in hot water or other solution and in order to be effective should be such that the fibers are brushed in a plurality of directions in order thoroughly to clean and polish them on all sides.

The operation known as "sizing" is, in a sense, the opposite of the jacking operation and is for the purpose of consolidating the body and increasing the interlocking of the fibers.

Referring to the drawings, 15 denotes side uprights or members of the main frame of the machine; 54 end members connecting said side members; 16 a table at each end of the machine; 17 aprons or work guides carried by the tables 16; and 18 a tank.

55 denotes an auxiliary frame carried by the uprights 15 and depending within the tank 18.

In operation the hat bodies are passed between upper and lower sets of rolls within the tank 18.

19 denotes the upper rolls which are carried by a frame 20, and 21 the lower rolls which are carried by a frame 22. The rolls 19 are preferably staggered with respect to the rolls 21, that is the axis of each roll 19 lies in a vertical plane intermediate the axes of two adjacent rolls 21. By this arrangement a hat body passed through the series of rolls between the upper and lower rolls is caused to remain in contact with the rolls substantially throughout its travel or for a considerably greater proportion thereof than would be the case were the rolls grouped in pairs one vertically above the other. The rolls 19 and 21 are connected in

pairs by gears 23, each roll 19 being connected to the roll 21 beneath and to the left thereof, as shown in Fig. 3. Preferably and as herein shown the rolls 21 are greater in number by one than the rolls 19, the roll 19 at the right of the series as shown in Figs. 1 and 3 being connected with both of the adjacent rolls below the same. The gears 23 of the rolls of one set are formed of a sufficient width to permit relative reciprocation of the two sets of rolls transversely of the machine, as hereinafter more fully described. Preferably, and in order to economize space, the gears 23 connecting the rolls 19 of the several pairs are arranged on the shafts 24 of said rolls alternately at opposite sides of the frame. The shafts 24 of the upper and lower rolls are journaled in boxes 31 and 32 preferably adjustably secured by bolts 33 and 34 to the upper and lower frames 20 and 22, respectively.

The character of the surfaces of the rolls 19 and 21 is in accordance with the character of the operation for which the machine is used. For the jacking operation said rolls are provided with suitable projections forming carding surfaces of a well known character, as by covering the same with the usual carding cloth. For the brushing operation brushing rolls of ordinary type are employed. For the sizing operation there may be employed rolls of the form shown in Fig. 10, said rolls being each composed of a series of disks 25 of wood mounted on the shaft 24 with the grain transverse to the axis of said shaft and clamped thereon, between fixed and loose collars 27 and 28 respectively, by means of a nut 26. Preferably, however, and as shown in Fig. 11, a metallic sizing roll composed of some non-corroding metal, such as brass or bronze and provided with a roughened surface is employed, such a roll being considered of material advantage over the usual wooden roll which in time is likely to splinter and cause the splinters to enter the hat body, thereby damaging the same.

In order to permit certain of the rolls, particularly the brushing rolls, to be easily and quickly removed and replaced, said rolls 50 are preferably formed in two semi-cylindrical sections, as shown in Fig. 6, which are assembled about the corresponding shaft 24 and held in place thereon by a collar 29 (see Fig. 7) slipped over the reduced ends 30 of 55 said sections and secured in place by pins passing through suitable openings in said collar, end portions 30, and shaft 24.

35 (see Fig. 1) denotes a driving shaft journaled in the machine frame, provided 60 with the usual belt pulleys 36, and connected with the roll shafts 24 by suitable transmission devices. As shown the shaft 35 is provided with sprockets 37 and 38 connected by chains 39 and 40 with sprockets 41 and 42 65 on the shafts 24 of the first two upper rolls

19, counting from the left in Figs. 1 to 3. Each of said last named shafts 24 is provided with a sprocket 43 connected by a chain 44 with the sprocket 45 on the second shaft 24 of the series toward the right. The 70 arrangement of these transmission devices or driving connections is such as to provide for driving the several rolls at relative velocities determined by the character of the operations to be performed, as will now be 75 explained.

In the brushing operation it is desirable that the pairs of rolls have a progressively accelerated movement, this being the arrangement shown in Fig. 1, from which it 80 will be seen that the second roll 19 counting from the right will be rotated at a slightly greater speed than the first, the third at a greater speed than the second, the fourth at a greater speed than the third and so on 85 through the series. In operation the hat bodies are fed into the machine from the apron 17 at the right in Fig. 3 and between the first pair of rolls, pass through the entire series of rolls, and are discharged 90 upon the apron 17 at the left. As the second and third pairs of rolls are each rotated faster than the preceding pair, one pair of rolls is in effect brushing the nap forward while the other pair is brushing 95 it backward, this for the reason that, while both pairs of rolls are turning forward, as the forward pair is turning relatively fast the slower movement of the first pair gives the effect of brushing the nap backward. Simultaneously with this brushing of the nap forward and backward the nap is brushed in each direction transversely by a relative lateral movement of the rolls of the upper and lower set respectively as here- 100 inafter described.

For the operation of jacking transmission devices are preferably provided which will cause all of the rolls to be rotated at the same speed, so that the small points of the 110 carding or other jacking covering gently withdraw the ends of the fibers from the hat body. While it would be possible to employ the machine for jacking operations with rolls having a progressively accelerated 115 movement, as above described in connection with the brushing operation, this would cause a more severe treatment of the body, breaking and completely withdrawing a considerable number of fibers.

In employing the machine for sizing operations a series of transmission devices providing for progressively retarded movement of the rolls is employed. In order to produce a sizing effect, a squeezing or pressing 125 together of the fibers is necessary. If, therefore, the rolls be operated in such a manner that each succeeding pair of rolls rotates at a slightly less speed than each preceding pair, there will be a tendency for one set of 130

rolls to push the hat body against the resistance of the slower movement of the succeeding pairs of rolls. The same results may be accomplished by providing a series of sizing 5 rolls of varying diameters and employing driving connections for rotating all of said rolls at a uniform speed. Such an arrangement is illustrated in Fig. 12 wherein 96 denotes a series of sizing rolls of progressively 10 decreasing diameter from the right or front end of the machine to the left or rear end thereof. It will be seen that while the rolls 96 are all driven at the same angular velocity their peripheral velocities will progressively 15 diminish from the front to the rear of the machine, thereby producing the same sizing effect as in the case of a series of rolls of equal diameter driven at a progressively diminished speed.

20 46 denotes upright supporting arms pivoted at their lower ends upon studs 47 projecting from the machine frame adjacent the bottom thereof and at their upper ends upon pins 48 carried by the upper frame 20. The 25 arms 46 are arranged in pairs at opposite ends of the machine, whereby the frame 20 is supported for substantially horizontal movement transversely of the machine or parallel to the axes of the rolls. The arms 30 46 are preferably formed in two sections connected by sleeves 49, whereby the length of said arms may be adjusted. As shown, said sleeves 49, are in adjustable threaded engagement with the upper sections of said arms and form at their lower ends sockets which receive the lower unthreaded sections 35 of said arms, the upper ends of said lower sections preferably engaging stop pins 50 carried by said sleeves. The sleeves 49 are 40 preferably split and are clamped in adjusted position upon the sections of the arms 46 by means of bolts 95. With this arrangement, by loosening the lower bolts 95, the upper sections of the arms 46, together with 45 the sleeves 49, may be readily separated from the lower sections of said arms, thereby permitting the upper frame 20 to be raised in order to afford convenient access to the rolls carried thereby and to the lower 50 frame 22. The capacity for independent adjustment of the arms 46 by means of the sleeves 49 provides not only for the adjustment of the frame 20 toward and from the frame 22, but also for the relative angular 55 adjustment of said frames, thereby permitting the use of rolls of different diameters, as above described in connection with the sizing operation, and as shown in Fig. 12.

51 denotes lugs depending from the upper 60 frame 20 and carrying bearing members 52 which are held in adjusted position in said lugs by means of stop screws 53 and which engage the auxiliary frame 55 for the purpose of guiding the roll frame 20 in its lateral movements.

56 denotes brackets secured to the lower portions of the auxiliary frame 55 and formed at their upper sides with short raceways 57 (Fig. 5) extending transversely of the machine and in which are located rollers 58.

59 denotes bearing plates or members carried by the lower roll frame 22 and resting upon the rollers 58.

The raceways 57, rollers 58, and bearing 75 plates 59 provide an antifriction bearing for the frame 22, providing for a limited horizontal movement of said frame transversely of the machine or in a direction substantially parallel to the direction of movement 80 of the frame 20. When desired for purposes of obtaining convenient access to the lower rolls 21, or otherwise, and after the upper frame 20 has been raised, as above 85 explained, the lower frame 22 may be readily lifted from the rollers 58 and removed from the machine. Certain of the rollers 58, preferably two of each set, are provided with side flanges 60 (Fig. 12) which engage the outer faces of the raceways 57 and bearing plates 59, thereby serving to hold the frame 22 against movement longitudinally 90 of the machine and guiding its lateral movement.

For imparting the lateral movements 95 above referred to to the frames 20 and 22 the following mechanism is provided, reference being had to Figs. 1 to 5: 61 denotes a shaft mounted in journals 62 secured to the main frame of the machine, said shaft being connected, as by bevel gears 63, with the driving shaft 35. 64 denotes a crank disk secured to the shaft 61 and having a transverse guideway 65 in which is adjustably mounted a block 66 carrying a crank pin 67. 105 By adjusting the block 66 in the guideway 65 the throw of the crank pin 67 may be varied according to requirements. 68 denotes a link pivoted at one end to the crank pin 67 and at the other, by means of a pin 110 69, to an arm 70 secured to a rock shaft 71 journaled in brackets or ears 72 carried by the frame uprights 15. The arm 70 is preferably of the curved or gooseneck form 115 shown in Figs. 4 and 5 in order to extend over the edge of the tank 18. 73 denotes levers secured at their central portions to the shaft 71 and having arms extending upwardly and downwardly from said shaft. 74 denotes links pivoted at 75 to the upper 120 arms of the levers 73 and at 76 to ears 77 projecting from the upper frame 20. 78 denotes links pivoted at 79 to the lower arms of the levers 73 and at 80 to ears 81 on the lower frame 22. The pivots 75, 76, 79 and 125 80 preferably comprise removable pins, whereby either of the roll frames may be disconnected from the reciprocating mechanism. The links 74 and 78 are preferably arranged in pairs at opposite sides of the 130

levers 73 and ears 77 and 81. The shaft 61, crank disk 64 and crank pin 67, when rotated, operate, through the link 68 and arm 70, to rock the shaft 71, and through the 5 levers 73 and links 74 and 78 to reciprocate the frames 20 and 22 in opposite directions, thereby producing a relative lateral movement of the rolls 19 and 21 in a direction parallel to their length. The amplitude of 10 the reciprocation of the frames 20 and 22 may be adjusted by adjusting the block 66 in its guide 65. The links 74 are provided with arms 82 which extend over the upper members of the frame 20 and carry stop 15 screws 83. When the frame 21 is raised for the purpose of obtaining access to either set of rolls said frame will first turn about the pivots 76 independently of the links 74 for a slight distance until the top members 20 thereof engage the stop screws 83, after which said frame and links will turn in unison about the pivots 75, thereby completely separating the upper and lower frames and disengaging the gears 23.

25 A modified construction is illustrated in Figs. 8 and 9. In accordance with this modification the links 74 and 78 are adjustably connected with the arms of the levers 73, such connection being provided in the construction shown by forming each of the arms of the levers 73 with a series of openings 97 arranged in arcs of circles concentric respectively with the pivots 76 and 80. The removable pins constituting the pivots 75 and 30 79 are adapted to be engaged with any of the openings 97 of the corresponding series. By thus adjusting the points of connection of the links 74 and 78 with the levers 73 the amount of lateral movement given to each of 35 the frames 20 and 22 at each operation of the rock shaft 71 may be varied. Preferably the arrangement will be such as to provide for an adjustment of the parts in which either one or both of the frames will remain 40 stationary. As above explained the amount of movement given to both frames may be adjusted by means of the block 66, while the adjustment of the connections of said frames with the levers 73 provides for varying the 45 movement of either frame with respect to or independently of the other. In the construction last described the arms 82 are formed on separate yokes 84 pivoted on the pins 76 and having each a series of openings 85 50 adapted to receive a removable pin 86 which also passes through suitably disposed openings in the corresponding links 74. The openings 85 of each yoke 84 are arranged in the arc of a circle concentric with the corresponding pivot 76 and are so disposed as to 55 permit the connection of the yoke 84 with the links 74 in such a manner that, irrespective of the connection of said links with the lever 73, the stop screw 83 will be held in 60 relatively close proximity to the corresponding member of the frame 20.

87 denotes beams extending longitudinally of the machine outside the uprights 15 and upon which the tank 18 is supported. The beams 87 normally rest upon removable pins 88 which are inserted in suitably disposed openings in the uprights 15.

89 denotes stirrups embracing the beams 87 and carrying stop screws 90 upon which said beams rest.

91 denotes chains connected with the stirrups 89, passing over sheaves 92 carried by the uprights 15, and connected at their ends to shafts 93 journaled in said uprights 15 and provided with cranks or handles 94. By turning the cranks 94 the chains 91 may be wound upon the shafts 93, so that by removing the pins 88 the tank 18 may be raised and lowered into and out of its normal position, as shown in full lines in Figs. 2 and 3. Said tank is guided in its vertical movements by the engagement of the beams 87 with the uprights 15 and by engagement of the walls of said tank with the frame members 15, 54 and 55. The tank is, of course, normally supported on the pins 88 but may be lowered at will into the position shown in dotted lines in Fig. 3, or into any intermediate position, for the purpose of cleaning the tank, to afford easy access thereto in case a hat body passing through the machine should slip between the rolls into said tank, and also for the purpose of adjusting the depth of submersion of the rolls in the fluid contained in the tank.

The operations of the various parts of the machine have been fully explained in the course of the foregoing description, but the operation of the complete machine may be reviewed as follows: The tank 18, which is normally held in the position shown, is filled with a suitable liquid, usually boiling water, to a depth which will cover the lower rolls 21 and partly cover the upper rolls 19, so that the various operations are all performed while the hat bodies are immersed in said liquid. Said hat bodies are fed to the machine from the right end thereof in any position, it being wholly immaterial whether they are fed in tip first, or edge first, or brim first. After passing through the machine the bodies are closed or folded in a different position and are passed through again, the operation being repeated as many times as may be desirable.

When used as a jacking machine suitable jacking rollers may be employed together with driving connections whereby said rollers are all rotated at the same speed. As the hat bodies pass between said rolls the small points of the carding or other jacking covering on the rolls enter gently into the bodies and draw gently out as the body leaves the

rolls. In this way the fibers are drawn away from or out of the hat body in such a gentle way as not entirely to remove any considerable quantity of fibers from the body while 5 tending to draw out the tip rather than the butt ends of the fibers. Also by thus performing the jacking operation while the hat bodies are immersed in boiling water the fibers are softened, less liable to break, and 10 may be drawn out of union with the body more easily. If the mechanism be so adjusted as to give to the roll frames a slight sidewise reciprocation during the jacking operation, such movement will have a certain 15 sizing or tightening effect upon the body, offsetting the opening tendency caused by drawing some of the fibers out of union.

For the brushing operation suitable brushing rolls are employed and driven at a progressively accelerated speed which, as above 20 explained, tends to brush the fibers both forwardly and backwardly. The roll frame reciprocating mechanism is usually so adjusted as to give both of said frames a maximum throw, thereby causing a continual lateral movement of the rolls upon one another and brushing the fibers laterally in both directions, so that said fibers are brushed in four different ways. By passing 25 a hat body through the machine several times in different ways it will be seen that the fibers may be thoroughly brushed in substantially every direction. The lateral reciprocation of the rolls during the brushing 30 operation also has a certain sizing or tightening effect upon the hat body. It has been found in some grades of hats that the brushing and tightening of the body is accomplished better when the machine is so 35 adjusted that only one set of rolls is reciprocated, and by the preferred construction above described it will be seen that such adjustment may readily be effected.

When used as a sizing machine alone suitable sizing rolls will be employed together with driving connections whereby said rolls will be given a progressively diminishing peripheral velocity, this result being accomplished, as above explained, either by employing 40 a set of rolls all of the same diameter and driven at a progressively reduced speed or by employing a series of rolls of progressively reduced diameter all driven at the same speed. In addition to the sizing or 45 crowding effect upon the hat body produced by such a set of rolls, as above explained, in the direction in which said body is moving through the machine, there is also a sizing effect in the direction transverse thereto due 50 to the opposite reciprocation of the upper and lower sets of rolls, and in order to equalize the sizing in one direction with that in the other the amplitude of reciprocation of the roll frames is suitably adjusted by ad-

justing the position of the slide 66 in the 65 guide 65. This sizing operation is also greatly facilitated and the results greatly improved by being performed while the hat bodies are immersed in boiling water.

Having thus described our invention we 70 claim:

1. A machine of the character described comprising, in combination, upper and lower sets of rolls, means for rotating said rolls, and means for imparting reciprocatory 75 movement to both of said sets of rolls, said last named means being adjustable to vary the amount of movement imparted to each of said sets independently of the other.

2. A machine of the character described comprising, in combination, upper and lower sets of rolls, means for rotating said rolls, and means for imparting reciprocatory movement to both of said sets of rolls, said last named means being adjustable to vary 85 the amount of movement imparted to both of said sets of rolls, and being also adjustable to vary the amount of movement imparted to each of said sets of rolls independently of the other.

3. A machine of the character described comprising, in combination, upper and lower roll frames, upper and lower sets of rolls carried by said frames, means for rotating said rolls, links pivoted to said frames respectively, a rock shaft provided with oppositely extending arms, means for adjustably connecting said links, with said arms respectively, and means for oscillating said rock shaft.

4. A machine of the character described comprising, in combination, upper and lower roll frames, upper and lower sets of rolls carried by said frame, means for rotating said rolls, links pivoted to said frames respectively, a rock shaft provided with oppositely extending arms each having a series of openings arranged in an arc of a circle concentric with the pivot connecting one of said frames with the corresponding link, 110 and removable pins passing through said links and engaging said openings.

5. A machine of the character described comprising a main frame, a tank, an auxiliary frame supported by said main frame 115 and depending within said tank, raceways supported by said auxiliary frame within said tank, rollers in said raceways, a roll frame provided with bearing members resting upon said rollers, and a set of rolls carried by said roll frame.

6. A machine of the character described comprising a main frame, a tank, an auxiliary frame supported by said main frame and depending within said tank, raceways supported by said auxiliary frame within 125 said tank, rollers in said raceways, and a roll frame provided with bearing members rest-

ing upon said rollers, said rollers having end flanges engaging the sides of said raceways and the sides of said bearing members for guiding the movement of said frame on 5 said rollers.

7. A machine of the character described comprising a main frame, a roll frame, and a series of upright arms pivoted to said main frame and roll frame respectively whereby 10 said roll frame is supported on said main frame for movement transversely of the machine.

8. A machine of the character described comprising a main frame, a tank, an auxiliary frame supported by said main frame and depending within said tank, a lower roll frame mounted on said auxiliary frame within said tank for movement transversely of said tank, a lower set of rolls carried by 20 said lower roll frame, an upper roll frame, an upper set of rolls carried by said last named frame and coöperating with said first named rolls, and a series of upright arms pivoted to said main frame and upper roll frame respectively, whereby said upper roll frame is supported on said main frame for movement transversely of said tank.

9. A machine of the character described 30 comprising a main frame, a tank, an auxiliary frame supported by said main frame and depending within said tank, a lower roll frame mounted on said auxiliary frame within said tank for movement transversely of said tank, a lower set of rolls carried by 35 said lower roll frame, an upper roll frame, an upper set of rolls carried by said last named frame and coöperating with said first named rolls, a series of upright arms pivoted to said main frame and upper roll frame respectively whereby said upper roll frame is supported on said main frame for movement transversely of said tank, means for rotating said rolls, and means for imparting reciprocatory movements to both 45 of said roll frames.

10. A machine of the character described comprising a main frame, a roll frame, and a series of upright arms pivoted to said 50 main frame and roll frame respectively, whereby said roll frame is supported on said main frame for movement transversely of the machine, said arms being adjustable in length to vary the vertical position of said 55 roll frame.

11. A machine of the character described comprising a main frame, a roll frame, and a series of upright arms pivoted to said main frame and roll frame respectively 60 whereby said roll frame is supported on said main frame for movement transversely of the machine, each of said arms comprising two sections and a sleeve adjustably connecting said sections.

12. A machine of the character described comprising a main frame, a roll frame, and a series of upright arms pivoted to said main frame and roll frame respectively, whereby said roll frame is supported on said main frame for movement transversely of the machine, each of said arms comprising two separable sections whereby said roll frame may be raised from said main frame.

13. A machine of the character described comprising a main frame, a roll frame, and a series of upright arms pivoted to said main frame and roll frame respectively, whereby said roll frame is supported on said main frame for movement transversely of the machine, each of said arms comprising two sections and a sleeve carried by one of said sections and forming a socket which receives the end of the other of said sections.

14. A machine of the character described comprising a main frame, a roll frame, and a series of upright arms pivoted to said main frame and roll frame, respectively, whereby said roll frame is supported on said main frame for movement transversely of the machine, each of said arms comprising two sections and a sleeve adjustably connected to one of said sections and forming a socket which receives the end of the other of said sections.

15. A machine of the character described comprising a roll frame, means for supporting said frame adapted to permit lateral movement thereof and also to permit said frame to be raised, means for laterally reciprocating said frame including a link pivoted thereto, and means carried by said link and engaged by said frame when said frame is raised whereby said frame and link are caused to turn in unison.

16. A machine of the character described comprising a main frame, a roll frame, a series of upright arms pivoted to said main frame and roll frame, respectively, whereby said roll frame is supported on said main frame for movement transversely of the machine, each of said arms comprising two separable sections whereby said roll frame may be raised from said main frame, means for laterally reciprocating said roll frame including a link pivoted thereto, and means carried by said link and engaged by said roll frame when said roll frame is raised whereby said roll frame and link are caused to turn in unison.

17. A machine of the character described comprising a roll frame, means for supporting said frame adapted to permit lateral movement thereof and also to permit said frame to be raised, and means for laterally reciprocating said frame including a link pivoted thereto, an arm carried by said link, and a stop screw carried by said arm and

engaged by said frame when said frame is raised, whereby said frame and link are caused to turn in unison.

18. A machine of the character described comprising a roll frame, means for supporting said frame adapted to permit lateral movement thereof and also to permit said frame to be raised, means for laterally reciprocating said frame including a link pivoted thereto and a member detachably secured to said link and provided with a stop engaged by said frame when said frame is raised, whereby said frame and link are caused to turn in unison.

19. A machine of the character described comprising a roll frame, means for supporting said frame adapted to permit lateral movement thereof and also to permit said frame to be raised, means for laterally reciprocating said frame including a link pivoted thereto, and a member adjustably secured to said link and provided with a stop engaged by said frame when said frame is raised, whereby said frame and link are caused to turn in unison.

20. A machine of the character described comprising upper and lower roll frames, upper and lower sets of rolls carried by said frames, means for rotating said rolls, means for supporting said lower roll frame adapted to permit lateral movement thereof, means for supporting said upper frame adapted to permit lateral movement thereof and also to permit said frame to be raised, links pivoted to said frames respectively, a rock shaft provided with oppositely extending arms, means for oscillating said rock shaft, means for adjustably connecting said links with said arms respectively, and a member adjustably secured to the link pivoted to said upper frame and provided with a stop engaged by said frame when said frame is raised, whereby said frame and link are caused to turn in unison.

21. A machine of the character described comprising a roll frame, means for supporting said frame adapted to permit lateral movement thereof and also to permit said frame to be raised, means for laterally reciprocating said frame including a link pivoted thereto and provided with a series of openings, a member pivoted to said link, a removable pin passing through said member and adapted to be engaged in any one of said openings, and a stop carried by said member and engaged by said frame when said frame is raised, whereby said frame and link are caused to turn in unison.

22. A machine of the character described comprising a roll frame, means for supporting said frame adapted to permit lateral movement thereof and also to permit said frame to be raised, means for laterally reciprocating said frame including a link, a

pin pivotally connecting said frame and link, a yoke pivoted on said pin, said yoke being provided with a series of openings arranged in an arc of a circle concentric with said pin, a removable pin passing through said link and adapted to engage any one of the openings in said yoke, and a stop carried by said yoke and engaged by said frame when said frame is raised, whereby said frame and link are caused to turn in unison.

23. A machine of the character described comprising a roll frame, means for supporting said frame adapted to permit lateral movement thereof and also to permit said frame to be raised, a link, a pin pivotally connecting said frame and link, a yoke pivoted on said pin, said yoke being provided with a series of openings arranged in an arc of a circle concentric with said pin, a rock shaft, an arm on said rock shaft having a series of openings also arranged in an arc of a circle concentric with said pin, a removable pin passing through said link and adapted to engage any one of the openings in said arm, a second removable pin passing through said link and adapted to engage any one of the openings in said yoke, and a stop carried by said yoke and engaged by said frame when said frame is raised, whereby said frame and link are caused to turn in unison.

24. A machine of the character described comprising a lower roll frame, a lower set of rolls carried by said frame, an upper roll frame, an upper set of rolls carried by said last named frame, gears connecting the rolls of said upper and lower sets in pairs, means for supporting said upper frame adapted to permit lateral movement thereof with respect to said lower frame and also to permit said upper frame to be raised, means for laterally reciprocating said upper frame including a link pivoted thereto and means carried by said link and engaged by said upper frame when said frame is raised, whereby said upper frame and link are caused to turn in unison and disengage said gears.

25. A machine of the character described comprising a tank and a series of rolls normally located within said tank, said tank being vertically movable toward and away from said rolls.

26. A machine of the character described comprising a main frame, a tank, an auxiliary frame supported by said main frame and depending within said tank, said tank being guided for vertical movement between said main and auxiliary frames, and a series of rolls located within said tank when said tank is in its uppermost position.

27. A machine of the character described comprising a main frame, a tank, an auxiliary frame supported by said main frame

and depending within said tank, said tank being guided for vertical movement between said main and auxiliary frames, a roll frame mounted on said auxiliary frame for movement transversely of said tank, and a set of rolls carried by said roll frame.

28. A machine of the character described comprising a tank, a series of rolls normally located within said tank, said tank being vertically movable toward and away from said rolls, and means for supporting said tank in its normal position with respect to said rolls.

29. A machine of the character described comprising a frame, a tank vertically movable in said frame, a series of rolls located within said tank when said tank is in its uppermost position, a pair of beams carried by said tank, and a series of removable pins carried by said frame upon which said beams rest when said tank is in uppermost position.

30. A machine of the character described comprising a tank, a series of rolls normally located within said tank, and means for moving said tank in a vertical direction toward and away from said rolls.

31. A machine of the character described comprising a frame, a tank, a series of rolls normally located within said tank, said tank being vertically movable toward and away from said rolls, chains connected with said tank, sheaves mounted on said frame over which said chains pass, shafts journaled in said frame upon which said chains are wound, and handles for turning said shafts to raise and lower said tank.

32. A machine of the character described comprising a frame, a tank, a series of rolls normally located within said tank, said tank being vertically movable toward and away from said rolls, a pair of beams carried by said tank, stirrups embracing said beams, chains connected with said stirrups, sheaves mounted on said frame over which said chains pass, shafts journaled in said frame upon which said chains are wound, and handles for turning said shafts to raise and lower said tank.

33. A machine of the character described comprising a frame, a tank vertically mov-

able in said frame, a series of rolls located within said tank when said tank is in its uppermost position, a pair of beams carried by said tank, a series of removable pins carried by said frame upon which said beams rest when said tank is in uppermost position, stirrups embracing said beams, chains connected with said stirrups, sheaves mounted on said frame over which said chains pass, shafts journaled in said frame upon which said chains are wound, and handles for turning said shafts to raise and lower said tank.

34. In a machine of the character described, a series of sizing rolls and driving connections for rotating said rolls, said parts being constructed and arranged to produce a progressively retarded movement of the surfaces of said rolls.

35. In a machine of the character described, a series of sizing rolls of progressively decreasing diameter, and means for rotating said rolls at a uniform speed.

36. In a machine of the character described, a plurality of pairs of sizing rolls, driving connections for rotating said rolls, said parts being constructed and arranged to produce a progressively retarded movement of the surfaces of the pairs of rolls, and means for imparting reciprocatory movement in a group to one set of rolls transversely of the machine.

37. In a machine of the character described, a plurality of pairs of sizing rolls, driving connections for rotating said rolls, said parts being constructed and arranged to produce a progressively retarded movement of the surfaces of the pairs of rolls, and means for imparting reciprocatory movement in a group to one set of rolls transversely of the machine, said last named means being adjustable to vary the amount of said movement.

In testimony whereof we affix our signatures in presence of two witnesses.

JOHN H. STARR.
JAMES F. DORAN.
